UNITED STATES PATENT OFFICE.

ARIE HOP, OF MAURICE, IOWA.

RADIATOR-DRAINING ATTACHMENT.

Application filed April 12, 1922. Serial No. 551,954.

To all whom it may concern:

Be it known that I, ARIE HOP, a citizen of the United States, residing at Maurice, in the county of Sioux and State of Iowa, have invented a new and useful Radiator-Draining Attachment, of which the following is a specification.

This invention aims to provide novel means whereby the drain cock on the radiator of an automobile may be opened and closed from the seat of the vehicle, without rendering it necessary for the driver of the vehicle to alight and crawl or reach under the vehicle. Another object of the invention is to provide novel means whereby the drain cock may be cleaned.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention, parts being in section; Figure 2 is a section on the line 2—2 of Figure 1; Figure 3 is a section on the line 3—3 of Figure 1; Figure 4 is a fragmental top plan showing the universal joint; Figure 5 is a section taken through the cleaner and showing, in elevation, a portion of the lever which cooperates with the cleaner; Figure 6 is a section on the line 6—6 of Figure 5.

The device forming the subject matter of this application is adapted to be mounted in various ways on an automobile, depending upon the nature thereof. By way of illustration, however, there is shown at 1, the oil pan which extends beneath or about an internal combustion engine on an automo-

bile, a portion of the radiator being shown at 2, and the drain cock for the radiator being marked by the numeral 3; the pan 1 having an opening 4 through which the drain cock projects. The drain cock may have a passage 5 controlled by a valve 7 journaled for rotation in the body of the drain cock, the valve having a port 6 adapted to be brought into and out of registration with the passage 5 when the valve is rotated. The turning head of the valve is designated by the numeral 8. The dash board of the vehicle is shown at 9.

A bearing 10 is secured at 20 to the oil pan 1 in any desired way, the bearing preferably but not necessarily, being disposed below the oil pan, since the drain cock 3, in the present instance, projects through the oil pan. A rotatable member 11 is carried by the bearing 10. A rotatable member 11 embodies a tube 12 journaled in the bearing 10. Any desired means may be provided for effecting a connection between the tube 12 and the turning head 8 of the valve 7 of the drain cock 3. If desired, the tube 12 may be provided with a reduced extension 14 having a notch or seat 15 adapted to receive the turning head 8. The construction is such that the tube 12 cannot move to the left (Figure 1) because the part 14 is engaged with the turning head 8 of the drain cock. The tube 12 cannot move to the right, because the tube has, intermediate its ends, an annular flange 43 cooperating with the bearing 10. The bearing 10 preferably comprises laterally separable parts, as shown at 50 in Figure 2, to the end that the tube 12 may be placed readily in the bearing. Diverging arms 16 project rearwardly from the tube 12. The arms 16 are united by pivot elements 18 with oppositely disposed portions of a ring 17.

The numeral 19 designates, generally, an operating member whereby rotation may be imparted to the tube 12. The operating member 19 may consist of an inner tube 21 and an outer tube 22 telescoped on the inner tube 21, the outer tube being journaled for rotation in the dash board 9. A set

2
screw 23, threaded into the tube 22 engages the tube 21 and holds the tubes together for rotation. At its inner end, the tube 21 terminates in a fork 24 connected by pivot elements 25 with opposite portions of the ring 17, the axis of the pivot elements 25 being disposed at right angles to the axis of the pivot elements 18. Generally stated, the construction is such that a universal joint connection is afforded between the operating member 19 and the tube 12 of the rotatable member 11. The tube 22 carries an enlarged head 26 located to the rear of the dash board 11, the head constituting means whereby rotation may be imparted readily to the tube 22 and, consequently, to the tube 21, since these parts are connected by the set screw 23. Owing to the fact that the operating member 19 comprises the telescoped elements 21 and 22, the operating member may be elongated or shortened at will, to accommodate the distance between the dash board and the engine in vehicles of different makes.

25 The tube 12 of the rotatable member 11 has a depending arm 27 whereon a bell crank lever 28 is fulcrumed at 29. One arm of the bell crank lever 28 extends through an opening 30 in the tube 11. At 30 its upper end, the bell crank lever 28 is supplied with a connecting element 31, whereunto one end of a retractile spring 32 is connected, the retractile spring being located within the tube 12. The other end 35 of the retractile spring 32 is carried by a securing element 33 mounted in the tube 12 adjacent to the part N thereof.

The numeral 34 denotes a flexible element or actuating device which may be a piece 40 of wire. The flexible element 34 extends through the telescoped elements 21 and 22 and terminates at its rear end in a button 35. The forward end of the flexible element 34 is attached by a member 31 to the upright 45 arm of the bell crank lever 28. Adjacent to its forward end, the tube 12 of the rotatable member 11 carries a depending bracket 36 terminating in a bearing 37 having a bore 38, the bearing being equipped with a lateral 50 opening 39 communicating with the bore 38. A cleaner 40 in the form of a plunger, is mounted for reciprocation in the bore 38 of the bearing 37, and is alined with the 55 passage 5 in the drain cock 3. The forwardly presented arm of the bell crank lever 28 terminates in a fork 41, spanning the cleaner or plunger 40 and received in the opening 38 of the bearing 37. A fork 41 may be provided with a recess 42 adapted 60 to receive a projection 44 on the plunger 40.

In practical operation, rotation may be imparted to the members 22 and 21 through the instrumentality of the head 26, the fork 24, the ring 17, and the arms 16 imparting 65 rotation to the tubular member 12. When

the tubular member 12 is rotated, its extension 14 will be rotated, and rotation will be imparted to the valve 7 of the drain cock 3, thereby to aline the port 6 in the valve with the passage 5 in the drain cock, whereupon 70 the water in the radiator 2 will run out, through the drain cock. Its construction, clearly, is such that the operator of the vehicle may open the drain cock and run the water out of the radiator 2 without dismounting from the vehicle. 75

Longitudinal reciprocation may be imparted to the flexible element 34, this element having sufficient stiffness so that it will impart swinging movement to the bell crank 80 lever 28 on the fulcrum 29, the spring 32 being elongated, and the cleaner or plunger 40 being raised, so that the cleaner will enter the passage 5 of the drain cock 3, thereby clearing out the passage, should any 85 obstruction become lodged in the lower end of the passage. When the pull is released on the button 35, the spring 32 reacts, and restores the parts to the positions shown in Figure 1, the upright arm of the bell crank 90 lever 28 abutting against the tube 12 at the forward end of the opening 30.

What is claimed is:—

1. In a device of the class described, a cock comprising a rotatable valve; a rotatable member connected to the valve; a cleaner for the cock and mounted directly on the rotatable member to swing therewith; and means for operating the cleaner. 95
2. In a device of the class described a cock comprising a rotatable valve; a rotatable member connected to the valve; a cleaner for the cock and mounted on the rotatable member to swing toward and away from the cock when said member is rotated; and mechanism carried by the rotatable member for operating the cleaner. 100
3. In a device of the class described, a cock comprising a rotatable valve, a rotatable member connected to the valve; a cleaner for the cock and mounted for reciprocation on the rotatable member; a lever fulcrumed on the rotatable member and connected to the cleaner; and means for operating the lever. 105
4. In a device of the class described, a cock comprising a rotary valve; a rotatable member; tubular means for rotating said member; means for connecting the rotatable member with the valve; a cleaner for the cock and mounted on the rotatable member; and mechanism for operating the cleaner, a portion of said mechanism extending through said tubular means. 110

5. In a device of the class described, a cock comprising a rotatable valve; a rotatable member connected to the valve; a longitudinally extensible tubular operating member connected to the rotatable member to rotate the same; a cleaner for the cock; 115

mechanism for holding the operating member at adjustable lengths; and means for operating the cleaner, a portion of said means being disposed within the tubular 5 operating member.

6. In a device of the class described, a cock comprising a rotatable valve, a cleaner for the valve, a single means for rotating the valve and for swinging the cleaner to-

ward and away from the cock, and means 10 for operating the cleaner.

In testimony that I claim the foregoing as my own, I have hereto affixed my signature in the presence of two witnesses.

ARIE HOP.
